UNITED STATES PATENT OFFICE

GABRIEL DEMAY, OF WEST NEW YORK, NEW JERSEY

DESIGN FOR A RING OR SIMILAR ARTICLE

Application filed March 10, 1931. Serial No. 39,022. Term of patent 3½ years.

To all whom it may concern:

Be it known that I, GABRIEL DEMAY, a citizen of the United States, and a resident of the city of West New York, in the county of Bergen and State of New Jersey, have invented a new, original, and ornamental Design for a Ring or Similar Article, reference being had to the accompanying drawing, forming part thereof.

Fig. 1 is a side elevation of a ring embodying my design.

Fig. 2 is a top plan view thereof.

Fig. 3 is a perspective view of a ring embodying my design.

I claim:

The ornamental design for a ring or similar article, as shown.

GABRIEL DEMAY.
